Thomas E. Ciesco(57) **CLAIM**

The ornamental design for "anti-vandal plate," as shown and described.

DESCRIPTION

FIG. 1 is a front elevational view of an anti-vandal plate showing our new design;

FIG. 2 is a top plan view thereof;

FIG. 3 is a rear elevational view thereof;

FIG. 4 is a bottom plan view thereof;

FIG. 5 is a left side elevational view thereof, the right side elevational view being a mirror image thereof; and,

FIG. 6 is a perspective view thereof.
